DESIGN FOR A BADGE

Harold H. Karr, San Diego, Calif.

Application June 22, 1934, Serial No. 52,273

Term of patent 14 years

To all whom it may concern:

Be it known that I, Harold H. Karr, a citizen of the United States of America, residing at San Diego, in the county of San Diego and State of California, have invented a new, original, and ornamental Design for a Badge, of which the following is a specification, reference being had to the accompanying drawing, forming a part thereof.

Figure 1 is a front elevational view of my new design for badge and Fig. 2 is an end edge view thereof.

The badge is plain on the back side thereof.

I claim:

The ornamental design for a badge, substantially as shown and described.

In testimony whereof, I have hereunto set my hand at San Diego, California, this 19th day of June 1934.

HAROLD H. KARR.
